UNITED STATES PATENT OFFICE

160,704

TYPEWRITER

Gerald K. Geerlings, New Canaan, Conn., assignor to Remington Rand Inc., New York, N. Y., a corporation of Delaware

Application April 7, 1949, Serial No. 1,842

Term of patent 7 years

(Cl. D64—11)

To all whom it may concern:

Be it known that Gerald K. Geerlings, a citizen of the United States, residing at Laurel Road, New Canaan, in the county of Fairfield, and State of Connecticut, has invented a new, original, and ornamental Design for a Typewriter of which the following is a specification, reference being had to the accompanying drawings forming part thereof:

Fig. 1 is a front perspective view of a typewriter showing the new design;

Fig. 2 is a side elevation looking at the left-hand side;

Fig. 3 is a plan view; and

Fig. 4 is a rear elevation thereof.

The essential features of the design for a typewriter reside in the parts shown in full lines.

The invention claimed is:

The ornamental design for a typewriter, as shown and described.

GERALD K. GEERLINGS.
